H. I. FINCH.
OSCILLATING ELECTRIC FAN.
APPLICATION FILED JULY 6, 1910.

978,147.

Patented Dec. 13, 1910.

UNITED STATES PATENT OFFICE.

HERBERT I. FINCH, OF ST. LOUIS, MISSOURI, ASSIGNOR TO EMERSON ELECTRIC MANUFACTURING COMPANY, OF ST. LOUIS, MISSOURI, A CORPORATION OF MISSOURI.

OSCILLATING ELECTRIC FAN.

978,147.

Specification of Letters Patent. Patented Dec. 13, 1910.

Application filed July 6, 1910. Serial No. 570,659.

To all whom it may concern:

Be it known that I, HERBERT I. FINCH, a citizen of the United States, residing at St. Louis, Missouri, have invented a certain new and useful Improvement in Oscillating Electric Fans, of which the following is a full, clear, and exact description, such as will enable others skilled in the art to which it appertains to make and use the same, reference being had to the accompanying drawings, forming part of this specification, in which—

Figure 1 is a general view of my improved fan with certain parts broken away, and other parts in section, so as to clearly show the novel construction. Figs. 2, 3 and 4 are detail views of certain novel features of construction.

My invention relates generally to electric fans and more particularly to that class of fans wherein the motor housing and fan blades oscillate or swing in order that the current of air created by the fan blades will be delivered throughout the arc of a circle, and the particular object of my invention is to provide simple means connected to the fan for automatically bringing about the oscillating or shifting movement.

To the above purposes my invention consists in certain novel features of construction hereinafter more fully described and claimed.

Referring by numerals to the accompanying drawings 1 indicates the fan base which is of ordinary construction, and has rotatively mounted thereon a motor casing 2. Within bearings for the casing is rotatably mounted the armature of an electric motor 3 the hub 5 of which is mounted to turn on a stationary hollow shaft or sleeve 4. To one end of the hub 5 is screwed the hub 6 of a fan 7. The hub 6 is hollowed out and threaded internally to screw upon the hub 5.

Beyond the screw threaded portion of the hub 6 is an opening 8, and in the center of the hub directly between the blades 7 the hub is bored or reamed out as at 9, and formed with an internal threaded portion 10, and a smooth bored portion 11. Within this portion of the hub 6 is screwed a plug 12 which has a suitable threaded periphery to fit into the internally threaded portion of the hub 6, and a smooth portion

to fit within the smooth bore 9. This plug 12 is formed as shown in fig. 2 with a smooth bore opening 13 and a cut away portion 14 forming projections 15 and 16 on either side thereof

Within the sleeve 4 and fitting in the opening 13 of the plug 12 is fitted a rod or spindle 15' having one end thereof flattened on either side as at 16' and a conically formed end 17. The other end of the rod 15' passes through a plug 18 screwed into the end of the hollow shaft 4 and has a worm 20 mounted thereon between the bearing 19, and another bearing 21 in the frame or standard. The worm 20 engages a gear 24 operatively connected with a mechanism indicated generally as 22 for oscillating the fan. This oscillating mechanism is old, and has been described and illustrated in the patent to myself and Charles R. Meston No. 952,458, and dated March 22, 1910. It is not necessary to describe this mechanism in detail as my invention does not include any specific features of this device.

The plug 11 has a dish-shaped face at 23 in order that the rod 15' may be easily positioned therein. The sleeve 4 fits within the hub 5 of the motor with a screwed end piece 25 attached forming a shoulder 26 to fit against one face of the hub 5. The other end of the sleeve 4 bears against the face 27 of the plug 18.

By use of my device the motor drives the fan, and a simple and direct connection is made between the fan and the mechanism for oscillating the motor on the base 1.

A fan of my improved construction is very simple and can be easily and quickly adjusted, and the oscillation or lateral swing of the motor and fan blades is accomplished by a simple positive connection between the fan and the oscillating means, which allows the worm and worm shaft of the oscillating means to be readily removed and renewed.

I am aware that various changes in the construction, arrangement and combination of parts may be made without departing from the spirit of my invention.

I claim:

1. The combination of a fan base, a motor pivotally mounted thereon, an armature having a fan connected thereto, said armature being mounted on a hollow sleeve, a motor oscillating means, and a device pass-

- ing through the hollow sleeve connecting the fan to the oscillating means.
2. The combination of a fan base, a motor pivotally mounted thereon, an armature mounted on a hollow sleeve, a fan mounted on the armature, a motor oscillating means, and a rod or spindle passing through the sleeve and connecting the fan to the oscillating means.
3. The combination with a fan base, of a motor pivotally mounted thereon, a fan connected to the armature of the motor, motor oscillating means, and a driving shaft detachably connected to the fan and extending through the armature of the motor and connected to the motor oscillating means.
4. In a device of the class described, a fan base, a motor housing pivotally mounted thereon, oscillating means carried by the motor, a hollow sleeve extending through the armature of the motor, a fan carried by the armature of the motor, and a shaft extending from the fan through the hollow sleeve to the motor oscillating means.
5. In a device of the class described, a fan base, a motor housing pivotally mounted thereon, oscillating means carried by the motor, a hollow sleeve extending through the armature of the motor, means for maintaining the hollow sleeve in position in the armature, a fan carried by the armature of the motor, and a shaft extending from the fan through the hollow shaft to the motor oscillating means.
6. In a device of the class described, a fan base, a motor pivotally mounted on said base, and carrying a fan motor oscillating means, a plug in the hub of the fan and a shaft having one end detachably seated in said plug, its opposite end being connected to the motor oscillating means.
7. In a device of the class described, a fan base, a motor pivotally mounted on said base, and carrying a fan motor oscillating means, a plug in the hub of the fan, a shaft having one end detachably seated in said plug, its opposite end being connected to the motor oscillating means, and a hollow sleeve inclosing said shaft and extending through the armature of the motor.
8. The combination of a fan base, a motor pivotally mounted thereon, an armature having a fan connected thereto, a motor oscillating means mounted on the base on the opposite side of the motor from the fan, a hollow sleeve upon which the armature is mounted, and operating means connected to the fan and to the oscillating means passing through the sleeve.
9. The combination of a fan base, a motor pivotally mounted thereon, an armature mounted on a hollow sleeve, a fan mounted on the armature, said fan having a hollow hub portion, said hollow sleeve having a screwed nut attached at one end to hold same in position and mounted in the hollow hub of the fan, a motor oscillating means, and means connecting the fan to the oscillating means passing through the hollow sleeve.

In testimony whereof I hereunto affix my signature in the presence of two witnesses, this 1st day of July, 1910.

HERBERT I. FINCH.
